United States Patent Office

Des. 217,593
Patented May 19, 1970

217,593

TACO HOLDER

James R. Loven, San Fernando, Calif.
(10965 Glenoaks Blvd., Pacoima, Calif. 91331)

Filed Mar. 19, 1969, Ser. No. 16,321

Term of patent 3½ years

Int. Cl. D9—04

U.S. Cl. D9—242

FIG.—1

FIG.—2

FIG.-3

FIG.-4

FIG.-5

FIG. 1 is a perspective view of the taco holder embodying my new design;

FIG. 2 is an end view thereof, both ends being alike;

FIG. 3 is a side elevation thereof, both sides being alike;

FIG. 4 is a plan view thereof;

FIG. 5 is a bottom view thereof.

I claim:

The ornamental design for a taco holder, as shown and described.
